UNITED STATES PATENT OFFICE.

JOHN W. CHAMBERLAIN, OF DALLAS, OREGON.

BURIAL-VAULT.

SPECIFICATION forming part of Letters Patent No. 633,804, dated September 26, 1899.

Application filed April 25, 1899. Serial No. 714,422. (No model.)

To all whom it may concern:

Be it known that I, JOHN W. CHAMBERLAIN, a citizen of the United States, residing at Dallas, in the county of Polk and State of Oregon, have invented a new and useful 5 Burial-Vault, of which the following is a specification.

This invention relates to burial-vaults, and has for its object to provide a device of this 10 character for efficient service and wherein the parts are simple, strong, and durable and adapted to be quickly and easily arranged for use.

The invention consists in the construction 15 and arrangement of the several parts, which will be more fully hereinafter described and claimed.

In the drawings, Figure 1 is a perspective view of a burial-vault constructed in accordance 20 with my invention, a portion of the lid or cover of the exterior shell being broken away to disclose the contained composite body portion of the vault. Fig. 2 is a longitudinal section of the same. Fig. 3 is a similar 25 view showing the outer shell, the lid or cover being omitted, the casket-supporting studs, the casket or core-box, and the composite vault proper up to the level of the upper surface of the core-box, and also showing 30 the upper or casket-retaining studs positioned for the introduction of the remaining portion of the material for forming the composite vault proper.

Similar reference characters indicate corresponding parts in all the figures of the drawings.

In the construction illustrated, 1 represents 35 an outer box or shell having a top or cover 2, which is adapted to be applied subsequent to the formation of the composite vault proper.

3 represents the hollow vault proper, which 40 is constructed of concrete or other composite material consisting of any preferred combination of sand and hydraulic cement.

45 4 represents a core or casket containing box which is inclosed by the vault proper, and 5 and 6 a series of lower and upper studs which respectively support the core-box and prevent the floating thereof during the setting 50 or hardening of the composite material forming the vault proper.

In practice I place upon the floor of the shell a series of four or more studs 5, which may be constructed of composite material, such as concrete or the equivalent thereof, and which 55 are corrugated, as clearly shown in Fig. 3, the length of these studs or blocks being that which is determined upon for the thickness of the bottom wall of the vault proper. After positioning these studs or blocks the bottom of the shell is filled to the level of the upper ends of the studs or blocks with the composite material which is to compose the vault proper. The core-box, which may consist of a casket or of the usual box in which 60 the casket is placed previous to interment, is then placed upon the upper ends of the spacing studs or blocks, as indicated in Fig. 3, and the space between the sides of the core-box and the walls of the shell is filled to the 65 level of the top of the core-box. Other studs or spacing-blocks 6, similar in construction to those which are arranged upon the bottom or floor of the shell, are then positioned at suitable intervals upon the top of the core-box, 70 and the remaining composite material which is to form the top of the vault proper is filled into the shell to the level of the upper ends of said studs or blocks, after which the lid or cover 2 of the shell is applied. The function 75 of the spacing studs or blocks 5 and 6 is to prevent the sinking of the core-box or the rising or floating thereof in the composite material during the setting or hardening of said material, whereby when completed the composite vault proper consists of walls of a uniform thickness with the core-box positioned centrally therein. Thus said studs or blocks 80 perform the functions of gage-blocks, which are of a length equal to the intervals, respectively, between the under surface of the core-box and the bottom of the shell and between the upper surface of the core-box and the top or cover of the shell, and, being exteriorly corrugated, these spacing or gage blocks become 85 thoroughly and permanently embedded in the material forming the walls of the vault proper or are interlocked therewith and combine with the same to complete the top and bottom walls 90 of the vault proper. When completed, therefore, the vault is of substantially integral construction when the spacing or gage blocks are 95 100

of the composite material which is used in the formation of the walls of said vault proper; but it will be understood that I do not desire to be limited to using the same material and 5 that various other changes in the form, proportion, size, and minor details of construction within the scope of the appended claims may be resorted to without departing from the spirit or sacrificing any of the advantages 10 of the invention.

Having described my invention, what I claim is—

1. A burial-vault, comprising an exterior shell, a contained core-box of precisely the same contour but smaller than the said shell and centrally located in the latter, a vault proper of one integral mass of composite material occupying the surrounding space between the bottom, top, sides and ends of the 15 core-box and the corresponding portions of the shell, and spacing-blocks embedded in the vault proper and terminally in contact re-

spectively with the top and bottom of the core-box and the top and bottom of the shell.

2. A burial-vault, comprising an exterior shell having the bottom, sides, and ends in planes at right angles to each other, a core-box of the same shape and smaller than the shell and centrally located in the latter, a vault proper of one integral mass of composite material completely occupying the space 25 between the core-box and the surrounding walls of the shell and spacing-blocks arranged in pairs between the tops and bottoms of the shell and core-box and embedded in the said 30 composite material.

In testimony that I claim the foregoing as my own I have hereto affixed my signature in the presence of two witnesses.

JOHN W. CHAMBERLAIN.
